UNITED STATES PATENT OFFICE.

ALBERT L. JOHNSON, OF WILERNIE, MINNESOTA.

SIGNAL FOR VEHICLES.

Application filed October 1, 1921. Serial No. 504,599.

My invention relates to improvements in signals for vehicles.

Its object is to provide a simple, durable and compact, electric signal pleasing in appearance and adapted for use in connection with vehicles to indicate premeditated changes in travel by displaying designating symbols, parts of said symbols being common to each other.

10 With the foregoing and other objects in view, which will appear in the following description, the invention resides in the novel combination and arrangement of parts and in the details of construction herein-
15 after described and claimed.

In the drawings, Fig. 1 is a vertical, central sectional view taken longitudinally of a device embodying my invention; Fig. 2 is a longitudinal sectional view taken on the 20 line 2—2 of Fig. 1 and Figs. 3 and 4 are elevations showing, in dotted lines, the two symbols as they appear when illuminated.

Referring to the drawings, I have used the reference character A to indicate an oblong signal housing, including top 10, bottom 11, ends 12 and side panels 13, said housing being adapted to be mounted by suitable means in any desired position upon a vehicle. The top, bottom and ends may be 30 formed of wood, sheet metal or other suitable material. The side panels 13 are of a material having the inherent quality of admitting light therethrough or may be of other material formed to accomplish that 35 end. I prefer to use a translucent material, such as frosted glass, though sheet metal formed with many minute perforations therein may be employed. Within the housing A, I arrange triangular partitions 14 forming, together with the panels 13, end compartments 15 and 16. A narrow intermediate compartment 17 reaching from one end compartment to the other is formed by horizontal partitions 18, together with portions of the partitions 14 and panels 13.

The intermediate compartment 17 outlines a central bar against each of the panels 13. The end compartment 16 outlines arrow heads, on said panels, pointing to the left, 50 and the compartment 15 outlines arrow heads, on the panels, pointing to the right, each outlined bar serving as the shaft of an arrow-like symbol for the different companion arrow heads. I supply a colored (red) electric lamp 19 for the end compartment 16, a colored (green) electric lamp 20

for the end compartment 15 and colored lamps 21 (red) and 22 (green) for the intermediate compartment 17. The lamps 19 and 21 are arranged in a circuit 23 and 60 the lamps 20 and 22 in a circuit 24, said circuits being adapted to be severally closed by any suitable mechanism. The closing of the circuit 24 results in displaying arrows on each side of the signal, the same being 65 of one color (green) and pointing to the right (Fig. 4). The closing of the circuit 23 results in displaying arrows on each side of the signal, the same being of another color (red) and pointing to the left (Fig. 3). 70

In using ground, frosted or other translucent material for the panels 13, I sometimes form opaque lines 25, upon the panels, as shown in Fig. 3, certain of said lines registering with the edges of the partitions 75 14 and 18. These opaque lines comprise patterns obscuring the outlines of the partitions against the panels 13, when the lighting circuits are open. When a lighting circuit is closed, and a symbol made visible 80 thereby, the pattern produced by said opaque lines is obscured and has no appreciable effect as viewed by an observer. I also contemplate the use of transparent panels patterned by cutting or molding (not shown) 85 to obscure the edges of the partitions 14 and 18.

It will be understood from the above description that the shaft of each arrow-like symbol is common to its companion symbol. 90 This arrangement provides for simplicity in structure, economy in manufacture, durability in use and renders the design most pleasing in appearance.

Changes in the specific form of my invention, as herein disclosed, may be made within the scope of what is claimed without departing from the spirit of my invention.

Having described my invention, what I claim as new and desire to protect by Letters 100 Patent is:

1. In a device of the class described, a light transmitting panel, partitions abutting thereagainst and forming adjacent compartments, a lamp within each compartment, 105 the light from each lamp outlined by the partitions of its respective compartment against said panel forming a portion of a direction indicating symbol, said panel having partition obscuring lines thereon, a plurality of said lines registering with the edges 110 of said partitions.

2. In a device of the class described, a light transmitting panel, partitions abutting thereagainst and forming adjacent compartments, some of said partitions being inclined, others vertical and others horizontal to form a direction indicating symbol, lamps within said compartments for illuminating portions of said panel included in a direction indicating symbol, said panel having
- 5 a plurality of inclined obscuring lines thereon, some of said lines registering with the
- 10

edges of said inclined partitions, a plurality of horizontal obscuring lines therein, some of said lines registering with the edges of said horizontal partitions, and a plurality of vertical obscuring lines, some of said obscuring lines registering with the edges of the vertical partitions.

In testimony whereof, I have signed my name to this specification.

ALBERT L. JOHNSON.
